UNITED STATES PATENT OFFICE.

EMIL A. KOPF, OF NEWARK, AND MARTIN HEMLEB, OF ELIZABETH, NEW JERSEY,
ASSIGNORS TO THE SINGER MANUFACTURING COMPANY, A CORPORATION OF
NEW JERSEY.

SEWING-MACHINE CABINET.

1,349,679.

Specification of Letters Patent. Patented Aug. 17, 1920.

Original application filed September 14, 1917, Serial No. 191,495. Divided and this application filed August 12, 1919. Serial No. 316,970.

To all whom it may concern:

Be it known that we, EMIL A. KOPF and MARTIN HEMLEB, citizens of the United States, residing, respectively, at Newark, in the county of Essex and State of New Jersey, and at Elizabeth, in the county of Union and State of New Jersey, have invented certain new and useful Improvements in Sewing-Machine Cabinets, of which the following is a specification, reference being had therein to the accompanying drawings.

This invention has for an object to provide a sewing machine cabinet of simplified construction including means for manually driving and controlling the sewing machine; the parts of the cabinet being arranged so that they may be conveniently shifted or folded in such a manner, when not in use, as to inclose the sewing machine and practically conceal the same together with the various controlling and driving devices therefor, whereby the complete outfit will have the neat and trim appearance of, and be adapted for use as, an ordinary table.

Further objects of the invention will appear from the following description and claim.

The invention, in its preferred embodiment, comprises a four-legged table, the top of which is apertured to receive and support the usual belt driven sewing head. Means are provided whereby the sewing head may be dropped or swung below the table-top; the latter including end-leaves which may be folded over to meet along the center line extending transversely of the table-top. A treadle is supported near the floor within the space defined by the table-legs and is connected by a pitman to a drive-wheel journalled at the under side of a lower leaf or shelf member which is hinged at one end to a cross-piece carried by an end pair of the table-legs and is adapted to be swung from a substantially horizontal position, concealing said treadle and drive-wheel, to an upright position exposing said treadle and drive-wheel and positioning the latter in operative relation to said treadle and to the driven pulley of the sewing head with which said drive-wheel may be connected by means of the usual belt.

In the accompanying drawings Figure 1 is an elevation of the invention with the parts in open or running position. Fig. 2 is a

similar view with the parts folded into closed or inoperative position. Fig. 3 is a vertical section on the line 3—3, Fig. 1. Fig. 4 is a fragmentary rear elevation of the treadle-control mechanism showing the operative connection between the treadle and driving pitman. Fig. 5 is a fragmentary plan view of the treadle. Fig. 6 is a perspective view of the retaining latch for the treadle concealing leaf or shelf and Fig. 7 is a sectional view showing the means for supporting one of the extension leaves of the table-top in the position shown in Fig. 1.

As disclosed in our copending application Serial No. 191,495, filed Sept. 14, 1917, of which this application is a division, the present cabinet, in its preferred embodiment, includes a table having a table-top 1 supported at its four-corners by legs 2, the end pairs of which are connected by upper and lower end braces or cross-bars 3 and 4, respectively, which support the spaced and vertically disposed end-slats 5.

The means incorporated in the cabinet for supporting the sewing head so that it may be swung or dropped from the position shown in Fig. 3 to a position below the level of the table-top are constructed substantially in accordance with the disclosure in the United States patent to Diehl *et al.*, No. 541,474; the rear side of the machine bed-plate being supported by the usual hinged pins, one of which is shown at 6, and the front side of said bed-plate resting upon the lip 7 of the hinged leaf 8. When the machine is to be dropped below the table-top 1 the hinged leaf 8 is first lifted to carry its lip 7 out of range of the front edge of the machine base, whereupon the machine may be lowered in the usual manner into the receptacle beneath the table-top. The usual counterbalancing spring 9 acts to partially support the machine head, all as more fully described in the said Diehl *et al.* patent.

In the present instance, the cabinet is equipped with any suitable belt driven sewing head. Such a sewing head usually includes a bed 10 from which rises a standard 11 carrying a bracket-arm 12 within which is journaled a main-shaft 12', Fig. 3, upon the rearwardly projecting end of which is secured the usual hand or balance-wheel 13 having a belt-groove 14 for the driving belt 15.

Hinged to the opposite ends of the table-top 1 are the extension leaves 16, 16, the left-hand one of which, Fig. 1, is supported in open position by the rod 17 which is 5 slidably received within the sheath 18 screwed to the under side of the table-top 1, as shown in Fig. 7. When the cabinet is closed, the extension leaves 16, 16 are folded over upon the table-top 1 and meet at the 10 center of the latter to conceal the aperture for the sewing head and form a smooth flat top for the cabinet which then has the appearance of a simple table.

Secured to the cross-bars 4 are brackets 15 19 formed with socketed bosses 20 in which are fixedly secured the opposite ends of the round tie-rod 21 which supports the treadle 22; the latter being formed with the depending apertured ears 23 entered by said tie-rod 20 and held in position longitudinally of the latter by suitable collars 24.

Hinged to the ledge 25 which projects inwardly from the right hand cross-bar 4 is the lower leaf or shelf member 26 on the 25 inner side of which is rotatably mounted the grooved drive-wheel 27 carrying a ball crank-pin 28 embraced by the socketed upper end of the pitman 29, the lower end of which carries a ball 30 embraced by the 30 socketed extension piece 31 which is detachably secured to the treadle 22 by screws 32. As will be observed, the socket of the extension piece 31 which embraces the ball 30 is formed of two separable disks 33 and 35 34 secured together and to the extension 31 by screws 35; said disks being cut away at one side to afford a clearance space 36 permitting the pitman 29 to assume the down turned position illustrated in Fig. 2.

40 The leaf 26 is retained in upright or running position by means of the latch 37 mounted to turn upon the stud-pin 38 carried by the plate 39 screwed to the inner face of the right-hand cross-bar 4, Figs. 45 and 3. The latch 37 comprises a stop 40

adapted to arrest the upward and outward movement of the leaf 26 and a retainer projection 41 adapted to be turned so as to project below the upper edge of the leaf 26 when in upright position, as shown in Fig. 1. 50 When the leaf 26 is lowered to closed or inoperative position, Fig. 2, the treadle and drive-wheel are substantially concealed from view: the ball-and-socket connections at the opposite ends of the pitman 29 permitting 55 closure of the leaf 26 without disconnection of said pitman from the treadle and driving wheel.

The cabinet is provided with suitable drawers for accessories and attachments. 60 The large center drawer 42 is hinged at 43 to swing outwardly and downwardly to open position, while the smaller end drawers 44 are slidably mounted in the usual manner.

The specific embodiment of the invention 65 shown and described is not intended to limit the scope of the appended claim as it will be apparent to those skilled in the art that the described construction is susceptible of material modification both in the form 70 and arrangement of the various parts within the spirit of the invention.

Having thus set forth the nature of the invention what we claim herein is—

A sewing machine cabinet comprising a 75 table-top, supporting means at the opposite ends of said table-top, a leaf forming a shelf carried by said supporting means below the table-top, a treadle mounted below and concealed by said leaf, said leaf being 80 pivotally sustained at one end of the table and adapted to be swung to an upright or open position at said end of the table to expose said treadle, and a drive-wheel mounted on said leaf and adapted for operative 85 connection with said treadle.

In testimony whereof, we have signed our names to this specification.

EMIL A. KOPE,
MARTIN HEMLEB.
